COATING MACHINE

Felix Eberhart, Arlington, N. J., assignor to
 American Can Company, New York, N. Y., a
 corporation of New Jersey

Application July 6, 1935, Serial No. 30,143

13 Claims. (Cl. 91—45)

The present invention relates to coating machines and has particular reference to machines for applying a plurality of overlapping layers of a liquid coating material to the interior surfaces 5 of container or can cylinders through the open ends of the cylinders and from a plurality of opposed directions.

An object of the invention is the provision of a can spraying machine for progressively spraying 10 the interior surface of open end can body cylinders by turning the can bodies or cylinders in one direction while spraying from one end and then in the opposite direction while spraying from the other end so as to cause the particles 15 of the coating material to intermix and flow together, thereby providing a continuous smooth protective coating of uniform thickness and unbroken consistency.

Another object is the provision in such a machine, 20 of a mechanism which guards the machine parts adjacent the spraying device from being coated or incrusted with spraying material while at the same time providing a gauge to insure proper coating of the flanges surrounding the open ends of the can bodies.

Another object is the provision in such a machine of instrumentalities for feeding and guiding lithographed cans through the machine in such a manner as to protect the lithographing 30 against scratching or marring.

Still another object of the invention is the provision in such a machine of electrically operated means for retarding the feeding of can bodies into the machine in timed relation with 35 the intermittent travel of a turret and electrically operated means for preventing the spraying devices from operating when no can body is present at a spraying station.

Yet another object of the invention is the provision in such a machine of an organized electric wiring system which automatically synchronizes all electrically connected operating parts to cause 40 them to work in timed cooperation, thereby permitting greater speed of operations.

Numerous other objects and advantages of the invention will be apparent as it is better understood from the following description, which, taken in connection with the accompanying drawings, discloses a preferred embodiment thereof.

Referring to the drawings:

Figure 1 is a view in front elevation of a can spraying machine embodying the instant invention, parts being broken away;

Fig. 2 is a view in side elevation of the machine showing its left side as viewed in Fig. 1, certain parts being broken away and shown in section;

Fig. 3 is a vertical sectional view taken substantially along the line 3—3 in Fig. 2;

Fig. 4 is a horizontal sectional view taken substantially along the line 4—4 in Fig. 1;

Fig. 5 is a sectional view taken substantially along the line 5—5 in Fig. 3; and

Fig. 6 is a wiring diagram of the electric circuit utilized in the machine.

In the machine disclosed in the drawings, cylindrical can bodies, having both ends flanged and open are fed into the machine from an inclined runway having an associated electrically 10 operated device for releasing the cans one at a time. The lower end of the runway terminates adjacent the path of travel of an intermittently rotating turret having a horizontal axis and radially disposed can pockets into which the cans 15 are individually positioned.

A pocket of the turret receives the lowermost can from the runway at station A and conveys the positioned can through two idle stations B and C and then to the first spraying station D. 20 Here the can is rapidly rotated in a clockwise direction in its turret pocket while the turret is briefly at rest and a spray of liquid coating material is projected against its interior surface through one of its open ends.

After several revolutions of the can the spray 25 is automatically cut off and the turret makes another of its intermittent movements until it comes to another dwell at spraying station E where the can is again rapidly revolved in a counter-clockwise direction.

Again the interior of the can is sprayed with the liquid coating material while the can is revolved but this time through the opposite end of the can. The can is thus sprayed from opposite 35 ends alternately while being revolved in opposite directions. This causes the particles of coating material while still wet to flow together and intermix with each other thereby covering the desired can surface with a protective film of even 40 thickness and unbroken consistency. At the completion of this spraying operation the spray is cut off.

Upon the next step rotation of the turret and while the turret is moving the can away from the 45 spraying station E it is dropped into an inclined discharge runway which carries it off to any suitable place of disposal.

A preferred form of apparatus embodying the instant invention as disclosed in the drawings, 50 comprises a turret 11, (Figs. 1, 2, 3 and 4) composed of a pair of spaced parallel discs 12 mounted on the end of a horizontal shaft 13 which is carried in a bearing 14, formed in a main frame 15, which supports the operating parts of the 55 machine.

Can body cylinders *a* are brought into the top of the machine at the can receiving station A in a continuous procession along an inclined runway 16. The can bodies have both ends open. 60

and are preferably provided with a flange *b* which later in another machine is interlocked with the flange of a can end to form a double seam. It should be understood, however, that the invention is not limited to spraying flanged open mouth cans but is also applicable to cans having the ends partially closed, such as for example friction plug cans having a friction sealing ring at both ends of the can, or hole and cap cans, or the like.

The runway comprises spaced and parallel can guides 17 secured to brackets 18, which in turn are bolted to the top of the frame 15. The lower end of the runway terminates adjacent the periphery of the turret 11.

In most cases the exterior surfaces of the can body *a* are already lithographed and it is desirable to protect these decorations against scratching or marring as the bodies pass through the machine. For this purpose the lowermost can body in the runway before entering the machine is arrested just above the turret periphery by a retarding device best illustrated in Fig. 5.

The device comprises an electric solenoid 21 which is bolted to the top of the frame 15 adjacent the can runway and which is equipped with a centrally located sliding rod or armature 22 which passes through the solenoid windings. One end of the rod is slidably carried in a bore 23 formed in bracket 18 and extends into the runway 16 projecting into an open end of the lowermost can body *a* holding the latter in a suspended position. The other end of the rod extends outside of the solenoid and is surrounded by a coiled spring 24 which is held in place by a collar 25 mounted on the extreme end of the rod.

The can body engaging end of the rod is held extended in the runway against the resistance of the spring 24 by electric energization of the solenoid. The solenoid is energized by current supplied from a generator forming a part of an electric circuit diagrammatically illustrated in Fig. 6, which will be explained hereinafter. It is only when the solenoid is deenergized that the spring withdraws the rod 22 from the runway thereby releasing a can body into the turret pocket.

The turret 11 is intermittently rotated in a step by step movement by its shaft 13, in turn rotated by any suitable means. The turret discs 12 are formed with can holding pockets 27 and as the turret pauses between rotations a pocket is positioned in alignment with a suspended can body *a* in the runway 16, at which time the solenoid rod 22 releases the lowermost can body and permits the remaining can bodies in the runway to move downward one step. The released lowermost can body falls into a pocket 27 at station A and the rod is again projected into the now lowermost can retarding it and those in back of it.

Each end of the pocket 27 is formed with an annular narrow raised rib 28 which engages the can body side wall behind each can body flange and away from the lithographing so that the latter will not be marred.

The turret is now moved through a step of its rotation carrying the can body away from the station A to an idle station B, while the other can bodies in the runway are held back by the rod 22.

The second step of rotation of the turret, carries the can body to an idle station C. After leaving the station B the can body engages a pair

of spaced arcuate guide rails 31 which hold it in its pocket 27. The guide rails extend along and are spaced away from the left hand outer edge of the turret as viewed in Figs. 1 and 3. The outer peripheries of the can flanges *b* ride on the inner surfaces of these guide rails to prevent disfiguration of the lithographing on the can body side wall.

At their upper ends the guide rails are spaced apart (Figs. 1 and 2) and are supported on a bar 10 32 carried in a boss 33 formed in the frame 15. At their lower ends they are held in spaced relation by a tie rod 34 and are also secured to the edges of a pair of spaced guard plates 35, which extend across the front and back of the lower 15 part of the turret. The plates 35 are also bolted to the upper ends of brackets 36 which in turn are secured to a table portion 37.

At stations B and C no operations are performed on the can body *a*, these stations being 20 merely incidental to locating the can at the next station which is spraying station D. On the next step in the rotation of the turret the can is carried to this station D which is located near the bottom of the turret.

In passing into the station the can body leaves the guide rails 31 and is held in a horizontal position in its pocket by and supported on a resilient roller 41. The roller is mounted on the body of a flat head screw 42 (Figs. 2 and 3) which 30 may be threadedly secured in a vertical web of a bracket 43 which is bolted to the top of the table 37. The roller is continuously rotated and through frictional engagement with the can side wall the can in turn is rapidly revolved while at 35 this station.

This rotation is effected by a gear 44 mounted on the screw 42 adjacent the roller 41 and secured to it. The gear meshes with an idler gear 45 which is mounted on a screw 46 carried in 40 the bracket 43 and this idler gear meshes with a driving gear 47. The driving gear is secured to the side of a sprocket 48 and both the gear and the sprocket are mounted on a screw 49 threadedly secured in the bracket 43.

The train of gears 44, 45, 47 is thus actuated by the sprocket 48 which in turn is driven by a chain 51 which meshes with a driving sprocket 52 (Fig. 1). The sprocket 52 is mounted on the end of a shaft 53 which is carried in a bearing 50 55 54 formed in a bracket 55, extending from the side of the table 37. The shaft 53 is continuously rotated in any suitable manner from the main driving shaft of the machine.

While the positioned can body is being rotated at station D a spray of liquid coating material is projected into it through its forward open end and against its interior side wall by a spray head 57 (Fig. 2) which is mounted on a bracket 58 formed as a part of a casing 59, which 60 in turn is secured to an inclined top pad of a bracket 61. This inclined position causes the spray head to tilt at a downward angle toward the forward open end of the can body.

The spray head is a standard commercial device of the spray gun type and comprises a nozzle 63 having an internal needle valve with a stem 64 for opening and closing the spray ejecting end of the nozzle.

A pipe 65 connecting with the spray head near the nozzle end delivers a liquid coating material to the nozzle under pressure from any suitable source of supply. At the opposite end of the spray head a connecting pipe 66 delivers com- 70 75

pressed air to the nozzle from a suitable source of supply.

When the needle valve is opened the compressed air ejects the coating material from the end of the nozzle and into the can body interior. The opening and closing of the valve is effected in timed relation with the step rotation of the turret, the opening of the valve taking place as soon as the turret positions a can at the station D. If no can body is in position when the turret pauses the valve does not open.

This is effected by a no-can-no-spray device having a can body engaging roller 68 (Fig. 3) of soft resilient material such as rubber which will not mar the lithographing of the can. The roller 68 is carried on one end of a substantially horizontal arm 69 of a bell crank lever 71 which is also provided with a vertical arm 72. The lever is pivotally mounted on a stud 73 which is carried

20 in a boss 74 formed in a bracket 75.

A can body arriving at station D engages the roller and pivots the bell crank lever on its stud 73 causing the vertical arm 72 to actuate an electric switch 76 (Figs. 3 and 5). To render 25 this action sensitive a counterbalance weight 77 is slidably mounted on a rod 78 (Fig. 3) having one end threadedly secured in a boss 79 formed on the lever 71. A set screw 81 threadedly engaging the weight is provided for locking it in 30 position on the rod when it is once adjusted.

The switch 76 is connected with a solenoid 83 (Fig. 2) and both are part of an electric circuit which will be fully explained in connection with the wiring diagram illustrated in Fig. 6. The 35 solenoid is housed in the casing 89 and is provided with a movable core rod 84, one end of which is connected by links 85 to the stem 64 of the nozzle needle valve. Through this connection a can body arriving at station D actuates the switch 76, 40 establishing a circuit which energizes the solenoid and moves the rod 84. The needle valve in the spray head 57 is thereby opened and a spray of coating material is projected into the can interior. When no can body arrives at station D 45 the solenoid is not energized and the needle valve remains closed.

The spray is directed downwardly against the interior side wall of the can body and against the flange of the can body through an opening 91 50 formed in the guard plate 35, which opening is directly in front of the can body end and is just large enough to expose the open end of the can body and its flange. The guard plate prevents the spray from being deposited on the turret and 55 other working parts of the machine.

To prevent gathering of coating material on the lower edge of the opening 91 a disc 92 is interposed between this edge and the path of the spray. The disc is disposed substantially below 60 the opening 91 with its outer circumferential edge just overlapping the lower edge of the opening so that the spray is deposited on the can body flange and the disc instead of the opening edge.

The disc is mounted on the end of a short shaft 65 93 which is carried in a bearing 94 formed in a bracket 95 which is bolted to the top of the table 37. The other end of the shaft carries a sprocket 96 which is connected by a chain 97 to a sprocket 98, mounted on the end of a driving shaft 99, 70 journaled in bearings 101 (Fig. 2), formed as a part of a bracket 102 which is bolted to the top of the table 37.

The lower part of the disc extends down into a solvent tank 105 secured to the front of the bracket 95 and closed at its top with a cover plate

106, leaving a slot opening for the disc. A wiper pad 107 of felt or other suitable material is held between the cover plate and a tank wall 108 and projects against the side of the rotating disc and 5 projects against the side of the rotating disc and wipes off any adhering undissolved coating material and solvent. In this manner excess coating material is prevented from gathering on the machine parts at undesirable places.

Excess spray and fumes which are blown through the can body are carried away by an 10 exhaust pipe or duct 111, located adjacent an opening 112 formed in the rear guard plate 35 at the rear open end of the can body. Such excess spray and fumes are drawn off in any suitable manner such as by an exhaust fan or blower 15 associated with the duct 111 but not shown.

At the end of the first spraying cycle the spray is cut off and the can body is advanced to the next station.

Thus far the interior side wall surface and the 20 flange adjacent one open end of the can body cylinder are coated with a layer of liquid coating material. The surface farthest away from this open end however is not coated as heavily as the end nearest the spray head. This is due to the 25 decrease in concentration of the spray as it extends further away from the spray head. The difference in the thickness of the coat is compensated, however, by repeating the spraying operation from the opposite open end of the can 30 as will now be explained.

The turret 11 now advances through another step of its rotation and in so doing carries the partially coated can away from the roller 41 and along supporting guide rails 121 (Figs. 2, 3 and 4). 35 These guide rails are thin plates which take the place of the ribs 28 and are secured by screws 122 to the sides of the brackets 36 and support the moving can body by engaging its exterior side wall just behind the end flanges so as not to mar 40 the lithographed outer surface.

When the turret next pauses or dwells the can body is in position at a spraying station E with its rear open end facing a spray head 123 (Figs. 3 and 4). This head is identical in construction 45 with that just explained in connection with station D and a detailed showing in the drawings and description is therefore deemed unnecessary. The head 123 is supported on a bracket secured to the side of the main frame in back of the 50 turret.

As the can body is brought into station E it actuates a bell crank lever 125 (Figs. 1, 2, 3 and 5) which constitutes a no-can-no-spray device identical with the device 71 employed at station 55 D. Lever 125 is mounted on the stud 73, between the lever 71 and the bearing 74 and has two arms 126, 127 similar to the arms 69, 72 of the lever 71.

The end of the arm 126 carries a rubber or the 60 like roller 128 which engages the can body exterior side wall without marring it and which actuates the lever when a can is brought into the station. The free end of the arm 127 extends in front of a movable part of an electric switch 129 65 which is part of the electric circuit to be hereinafter explained. Included in this circuit is a solenoid 130, diagrammatically shown in Fig. 6, and which is identical in construction and operation with the solenoid 83. The closing and 70 opening of the switch 129 energizes and de-energizes the solenoid thereby effecting the opening and closing of the needle valve of the spray head 123 at a predetermined time.

The can while at the station E is rapidly ro- 75

time with the stepped rotation of the turret 11. The switch is actuated by a cam 181 (see also Fig. 2). The cam is mounted on the end of a continuously moving shaft 182 which is journaled in bearings formed in the side of the main frame 15 and is rotated in time with the other parts of the machine in any suitable manner.

The cam 181 makes one complete revolution for each step of rotation of the turret 11 and is so timed as to close the switch 178 for a predetermined length of time when the turret stops with a pocket at station D. If a can is present in the pocket the no-can-no-spray device comprising the lever 72 and its associated parts, 15 closes the switch 76.

Under these conditions and when the service switches 163, 175 are closed, current from the generator passes through the circuit just described and energizes the solenoid 83. Energizing of the solenoid effects the movement of the rod 84 and the connected needle valve stem 64 which opens the valve causing the nozzle to eject a spray of coating material into the can. After a predetermined time the cam 181 opens 20 the switch 178 which breaks the circuit and stops the flow of current. This action de-energizes the solenoid and closes the nozzle needle valve which immediately cuts off the spray.

If no can is present in the turret pocket the 30 no-can-no-spray device does not close the switch 76 and thus the circuit is not completed. It is readily understood that under these conditions the solenoid is not energized and the spray nozzle needle valve is not opened. Thus when no can 35 is present to be sprayed the nozzle does not eject any spray.

When the turret stops a pocket at the station E, a circuit including the solenoid 130 and switch 129 becomes effective. This circuit is 40 similar to the one used at station D, and like this circuit one side of the solenoid, in this case the solenoid 130, is connected with the main service wire 164 by a wire 185. The other side of the solenoid is connected by a wire 186 to 45 one terminal post of a service switch 187. The opposite post of the switch is connected by a wire 188 to one side of the switch 129 which has its free side connected to the wire 177 by a short wire 189.

50 When a can is present in the turret pocket the no-can-no-spray device comprising the lever 127 and its associated parts, closes the switch 129. When this switch, the service switches 163, 187 and the cam actuated switch 178 which 55 serves this circuit also, are closed the circuit is complete and current flows through it.

The current flows through the service wire 164, wire 185, solenoid 130, wire 186, service switch 187, wire 188, switch 129, wires 189, 177, 60 through the switch 178, wire 179 and thence into the return service wire 166 back to the generator. Passage of current through this circuit energizes the solenoid 130 which in turn opens the spray head needle valve located at station 65 E and causes ejection of the spray from this head into the can.

When the switch 178 is opened the circuit is broken and the spray ceases as in the station D circuit. Likewise if no can is present in the 70 turret pocket the no-can-no-spray device will not close the switch 129 and the circuit will not be completed and no spray from the nozzle will be ejected.

It is thought that the invention and many of 75 its attendant advantages will be understood from

the foregoing description, and it will be apparent that various changes may be made in the form, construction and arrangement of the parts without departing from the spirit and scope of the invention or sacrificing all of its material 5 advantages, the form hereinbefore described being merely a preferred embodiment thereof.

I claim:

1. A spraying machine for coating with a liquid coating material the interior surface of container bodies having both ends open, comprising in combination, a rotary turret having peripherally spaced pockets for conveying container bodies in a circular path and to a plurality of spraying stations and a plurality of spraying devices at 15 said stations respectively and alternately disposed adjacent opposite ends of said positioned bodies for ejecting sprays of said material into said positioned bodies in alternately opposed directions, thereby covering the interior surface of 20 said bodies with a protective coating of uniform thickness.

2. A spraying machine for coating with a liquid coating material the interior surface of container bodies having both ends open, comprising 25 in combination, means for feeding a can body to a plurality of spaced spraying stations, means for axially rotating said body alternately in opposite directions at said stations, and spraying devices arranged at said stations respectively adjacent opposite ends of said body for individually and successively spraying the interior surface of said positioned body, first through one end of said body at one of said stations and then through the other end of said body at another of said stations, thereby covering the interior surface of said body with a protective coating 30 of uniform thickness.

3. A spraying machine for coating with a liquid coating material the interior surface of container bodies having both ends open, comprising 40 in combination, intermittently moving means for conveying a container body successively to a plurality of spraying stations in spray receiving position, means for individually rotating said 45 positioned body while at said stations, spraying means associated with each of said stations and alternately disposed adjacent opposite ends of said body for applying a plurality of layers of said material through alternately opposite open 50 ends of said body, whereby the layers of said material overlap and intermix, producing a protective coating of uniform thickness on the interior surface of said body, and exhaust ducts at each of said stations spaced from and at opposite sides of said conveying means for carrying away circulating fumes and excess coating 55 material.

4. A spraying machine for coating with a liquid coating material the interior surface of container bodies having both ends open, comprising 60 in combination, means for feeding a container body to a plurality of spaced spraying stations, means for axially rotating said body alternately in opposite directions at said stations respectively, spraying devices arranged alternately adjacent opposite ends of said body at said stations respectively for individually and successively spraying the interior surface of a said positioned body first from one end while it is 65 rotated in one direction at one of said stations and then from the other end while it is rotated in the opposite direction at another of said stations.

5. A spraying machine for coating with a liquid 75

- coating material the interior surface of container bodies having both ends open, comprising in combination, means for feeding a container body to a plurality of spaced spraying stations, 5 means for axially rotating said body alternately in opposite directions at said stations respectively, spraying devices arranged alternately adjacent opposite ends of said body at said stations respectively for individually and successively spraying the interior surface of a said positioned body first from one end while it is rotated in one direction at one of said stations and then from the other end while it is rotated in the opposite direction at another of said stations, and 10 15 electric means for controlling the time and duration of said spraying operation.
6. A spraying machine for coating with a liquid coating material the interior surface of container bodies having both ends open, comprising in combination, means for feeding a container body to a plurality of spaced spraying stations, means for axially rotating said body alternately in opposite directions at said stations respectively, spraying devices arranged alternately adjacent opposite end of said body at said stations respectively for individually and successively spraying the interior surface of a said positioned body first from one end while it is rotated in one direction at one of said stations and then 20 from the other end while it is rotated in the opposite direction at another of said stations and electric means operable by the presence of a said positioned body for actuating said spraying means.
- 35 7. A spraying machine for coating with a liquid coating material flanged container bodies having both ends open, comprising in combination, means for locating a body at a plurality of spraying stations, spraying devices for directing a spray of said material against the interior surface and flanges of said positioned body, and a disk rotatable on its own axis associated with one of said spraying devices and interposed in the path of said spray for gauging the application 40 45 of said material to said flanges and for diverting and collecting excess material.
8. A spraying machine for coating with a liquid coating material flanged container bodies with both ends open, comprising in combination, 50 means for locating a body at a plurality of spraying stations, spraying devices for directing a spray of said material against the interior surface and flanges of said positioned body, a rotatable device associated with each spraying device 55 and interposed in the path of said spray for gauging the application of said material to said flanges and for catching excess material, and means associated with said gauging devices for removing said excess material.
- 60 9. A spraying machine for coating with a liquid coating material flanged container bodies having open ends, comprising in combination, a rotatable turret having a peripheral pocket for receiving and locating a body at a plurality of spraying stations, means for rotating said positioned body, spraying devices at said stations and successively operable for coating the interior of the body and the flanges surrounding both open ends of said body, said spraying devices directing their spray against said flanges and into said body interior alternately from opposite directions through the open ends of said posi-

tioned body, and a disc rotatable on its own axis arranged adjacent each spraying device for gauging the application of said coating material to said flanges and for diverting excess coating material.

10. A spraying machine for coating with a liquid coating material flanged can bodies having open ends, comprising in combination, means for locating a container body in spray receiving positions, means for rotating said positioned body, spraying devices for coating the interior of said body and the flanges surrounding the open ends of a said positioned body, a rotating disc associated with each device for gauging the application of said coating material to said flanges and for diverting excess coating material, a solvent tank in which said disc rotates for dissolving said diverted coating material, and a wiper for removing said dissolved material and solvent from said disc.

11. In a machine for spraying the interior surface of flanged container bodies having both ends open and provided with decorated exterior surfaces, comprising in combination, means for locating a said body in a spray receiving position, means for successively spraying the interior surface of said container bodies from opposite ends thereof, a roller of resilient material for rotating a said positioned can body while its interior is being sprayed, said roller engaging said decorated surfaces, and means associated with said locating means, and of narrow extent longitudinally of the can, for engaging and supporting a said can body about a restricted annular portion immediately adjacent the flange and outside said decorated surface to insure against marring of the latter.

12. The method of coating the interior surface of a container body having both ends open, comprising, spraying a liquid coating material against said surface through one end of said body while rotating said body in one direction, and then while the applied material is still wet spraying said surface through the other end of said body while rotating it in an opposite direction, whereby two overlapping layers of coating material intermix to produce a unitary coating of uniform thickness.

13. A spraying machine for coating with a liquid coating material the interior surface of container bodies having both ends open, comprising in combination, a plurality of spaced spraying stations each having a spraying device mounted adjacent thereto, said spraying devices being adapted for successively coating the interior surface of a said body with a plurality of layers of said material, a rotary turret having peripherally spaced pockets for conveying container bodies in a circular path intermittently past said spraying devices, said pockets respectively having an inwardly extending peripheral projection for spacing said container bodies away from the pocket walls to prevent marring of the can bodies, one of said devices being adapted to spray said bodies from one side of said turret at one of said spraying stations and another of said devices being adapted to spray said bodies from the opposite side of said turret at another of said stations, thereby covering the whole interior surface of said bodies with a coating of uniform thickness.

FELIX EBERHART.
